UNITED STATES PATENT OFFICE.

DARWIN HANAUER, OF LAGRANGE, ILLINOIS, ASSIGNOR TO KINNEY-ROME COMPANY, OF CHICAGO, ILLINOIS, A CORPORATION OF ILLINOIS.

BED-SPRING SUPPORT.

Application filed November 25, 1922. Serial No. 603,173.

The invention relates to means for supporting spring bed-bottoms in bedsteads and more particularly to supporting devices which can be adjusted to properly fit different wooden and metal bedsteads having side bars or ledges adapted to carry the bed-bottom. The invention seeks to provide supporting clips which can be readily and securely applied to the usual angle-bar side-rails of bed springs and positioned to engage the supporting side bars or ledges of wooden or iron bedsteads, and which can be readily adjusted to fit different bedsteads that vary somewhat from the standard widths. The invention consists in the features of construction hereinafter set forth, illustrated in the preferred form in the accompanying drawings and more particularly pointed out in the appended claims.

20 In the drawings:

Fig. 1 is a vertical section of a portion of a spring bed-bottom and of a bedstead side bar with the present improved supporting clip applied to the bed-bottom.

25 Fig. 2 is a plan view of the improved supporting clip applied in position upon the angle-bar side-rail of a spring bed-bottom.

Figs. 3 and 4 are vertical sections on the lines 3—3 and 4—4 respectively of Fig. 2.

30 The bed spring illustrated is of usual construction and comprises side-rails 1 connected by transverse members 2 which carry rows of springs 3, the latter being connected together and to a border wire 4 in any suitable or usual manner. As usual for strength and rigidity, the side-rails of the spring bed bottom are formed of angle bars and have upper outwardly projecting flanges *a* and inner vertical depending flanges *b*.

40 Such bed springs are made of different standard widths and the outwardly projecting flanges of the side-rails are adapted to engage the supporting side bars or ledges of wooden or iron bedsteads. But bedsteads of different manufacture, and particularly those of wood, frequently vary from the required width and it becomes necessary to provide additional means for properly supporting the spring bottom in position. The present invention provides an improved adjustable supporting device, one or more of which may be readily applied to the angle-bar side-rails of the spring, and adjusted and securely clamped in position to properly engage the supporting ledges of the bedstead.

The improved device comprises a supporting member or clip 5 which is conveniently formed of a short section of flat metal bar, is preferably provided with a rounded corner as shown and has a longitudinally extending central slot 6. This supporting clip is adapted to engage and extend across the upper horizontal flange *a* of the angle-bar side-rail 1 of the bed spring and project beyond its outer edge to properly engage the spring supporting ledge of the bedstead. Fig. 1 illustrates in section the side bar 7 of a wooden bedstead provided with the usual supporting ledge 8.

For clamping the supporting clip in position a U-shaped hook 9 is provided which is preferably formed of a short section of flat metal bar of slightly greater width than the supporting clip 5, the bar section being bent as shown to form relatively long and short 70 inner and outer members *c* and *d* connected by an intermediate portion *e*. The upper edge of the relatively long member *c* of the U-shaped hook is recessed or cut away to provide a guiding seat 10 for adjustably receiving the supporting clip 5 and lugs or shoulders 11 at the ends of the seat which are adapted to engage the side edges of the clip. A bolt 12 having a headed upper end extends through the slot 6 of the supporting clip 80 and through a hole 13 in the lower horizontal portion of the U-shaped hook 9, and a wing clamping nut 14 is threaded on the lower end of the bolt. 85

When applied in position the lower end 90 portion *e* is horizontally disposed beneath the lower edge of the vertical flange *b* of the side-rail and the members *c* and *d* of the hook are vertically disposed with the latter overlapping and engaging the outer face of the side-rail flange *b*, and the member *c* inside of and spaced from the rear face of the rail. The bolt 12 is of such size and is so disposed that it is arranged closely adjacent the rear face of the vertical flange *b* 100 and when the clamp nut thereon is tightened cooperates with the vertical member *d* of the hook to hold the latter and the supporting clip 5 securely in position on the side-rail.

Obviously, the improved supporting clip 105 can be applied to bed springs now in use and adjustably clamped in position on the side-rail thereon. Also, the clip 5 can be adjusted relatively to the hook member and bolt to project to a greater or less extent 110

beyond the outer edge of the horizontal flange *a* and can then be securely clamped in adjusted position. The guiding seat 10 in the upper end of the hook member having 5 lugs or shoulders 11 at its opposite ends prevents rotary movement of the supporting clip about the bolt and cooperates therewith to hold it in proper position.

The improvement provides an inexpensive, 10 adjustable, supporting clip for bed springs, which can be readily applied and adjusted and securely clamped in position upon the angle-bar side-rail by means of a single bolt. Changes may be made in the details set forth 15 without departure from the essentials of the invention as defined in the claims.

I claim as my invention:

1. Supporting means for bed-springs comprising, in combination with the angle-bar 20 side-rail of a bed-spring, an adjustable horizontal member engaging and extending across the upper face of said side-rail, a vertical member spaced from the inner face of said rail and having an outwardly projecting hook engaging the depending flange thereof, and a vertical bolt arranged adjacent the inner face of said rail for clamping said members thereto and for holding said horizontal member in adjusted position, 25 said vertical member having means for holding said horizontal member against rotation about said bolt, substantially as described.

2. Supporting means for bed-springs comprising, in combination with the angle-bar 35 side-rail of a bed-spring, a flat, longitudinally slotted, supporting clip engaging and extending across the upper horizontal face of said rail, a hook engaging the vertical depending flange of the rail and having a 40 vertical portion spaced from the inner face thereof and provided at its upper end with a guiding seat for the inner portion of said adjustable support, a bolt arranged adjacent the inner face of said rail and extending through the slot of said clip and the lower end portion of said hook, and a 45 clamp-nut threaded in the lower end of said bolt, substantially as described.

3. An adjustable support for bed springs 50 comprising a longitudinally slotted supporting clip, a hook, and a bolt extending through the slot of said clip and through said hook and arranged to extend across and adjacent the inner face of the angle-bar 55 side-rail of a bed spring and clamp the clip

and the hook in engagement respectively with the upper horizontal flange and the lower edge of the depending vertical flange of the rail, said clip and hook having interengaging parts at their inner ends for holding the clip against rotation about the bolt while permitting the longitudinal adjustment of the clip.

4. An adjustable support for bed springs comprising a longitudinally slotted supporting clip, a hook, and a bolt extending through the slot of said clip and through said hook and arranged to extend across and adjacent the inner face of the angle-bar side rail of a bed spring and clamp the clip and the hook in engagement respectively with the upper horizontal flange and the lower edge of the depending vertical flange of the rail, one of said clip and hook parts having an inner member parallel to but spaced inwardly from said bolt and adjustably engaging the inner end of the other of said parts.

5. An adjustable support for bed-springs comprising a supporting clip and a hook arranged to engage the horizontally and vertically depending flanges respectively of the angle-bar side-rail of a bed spring with the shank of the hook spaced from the inner face of the rail, and a vertical clamping bolt adapted to extend adjacent the inner face of the rail and through the lower U-shaped end of said hook and having a headed upper end adjustably engaging said clip, the shank of said hook having means for holding said clip against transverse movement, substantially as described.

6. An adjustable supporting clamp for bed-springs, comprising a flat, longitudinally slotted, supporting clip, a U-shaped hook formed of a bent section of a flat bar and having relatively long and short inner and outer members, said relatively long inner member having a guiding seat for adjustably receiving said clip, and a bolt extending through the slot of said clip and the lower end of said hook and adapted to clamp the same to the angle-bar side-rail of a bed-spring with the clip extending across the upper face of the rail and the vertical depending rail flange disposed between the bolt and the outer member of the hook, substantially as described.

DARWIN HANAUER.
